UNITED STATES PATENT OFFICE.

WILLIAM S. WELLS, OF ASTORIA, NEW YORK, ASSIGNOR OF ONE-HALF TO
MOSES C. MIGEL, OF NEW YORK, N. Y.

TENSION DEVICE.

SPECIFICATION forming part of Letters Patent No. 739,523, dated September 22, 1903.

Application filed October 18, 1902. Serial No. 127,454. (No model.)

To all whom it may concern:

Be it known that I, WILLIAM STOLL WELLS, a citizen of the United States, and a resident of Astoria, in the county of Queens and State 5 of New York, have invented certain new and useful Improvements in Tension Devices, of which the following is a specification.

My invention relates to tension devices for threads, and is more particularly designed to 10 apply tension to silk threads in process of winding them from large spools upon smaller spools or so-called "quills."

The object of my invention is to provide a tension device which will be extremely efficient and which will allow the thread to be moved at a very high rate of speed, which will allow the thread to be readily introduced into the tension device, and which will act in a uniform manner irrespective of the thickness 15 of the thread. The spool from which the silk thread is taken is generally held stationary and only the spool upon which the thread winds is revolved, and the axes of these two spools are preferably arranged at an angle to 20 each other.

An example of my invention is shown in the accompanying drawings, and the novel features of the improvement are pointed out in the appended claims.

30 Figure 1 is an elevation showing the general arrangement of the tension device with parts in section. Fig. 2 is a plan of the tension device proper, and Fig. 3 is a cross-section thereof on line 3 3 of Fig. 2.

35 A indicates the spool from which the thread B is taken, and preferably the spool, together with its holder A', is stationary and the thread is wound upon it, so that the spool increases in diameter toward one end, thereby enabling 40 the thread to readily wind off without a rotation of the spool A.

C is a stationary guide or eye for giving the thread the proper direction through the tension device proper to the winding-spool 45 D, which is rotated, with its holder, in any suitable manner. For instance, the spindle D' may constitute a rotary spool-holder. It will be observed that the axes of the spools A and D are located at an angle to each other, preferably at a right angle. The tension device is located so as to receive that portion of the

thread which is between the guide C and the spool D. This tension device comprises a base E, to which is secured a plate F, having a very smooth upper surface. This plate 55 may, for instance, be made of glass and extends beneath the thread B, as shown best in Fig. 2. The thread thus passes over said plate with but little friction.

Above the base E and plate F is arranged 60 a frame G, held in position by a wing-nut H, which screws on a projection H' from the base E. This frame is provided with one or more apertures G', which allow access to the pressure-exerting device to be described presently. At its free end the frame G is provided with a depending lip G², which terminates at a distance from the base E, so as to leave a slot G³, through which the thread B may be inserted into the tension device side- 70 wise without taking the tension device apart. At about its center the frame G is provided with projections G⁴, and at the ends similar projections G⁵ are located. Adjacent to the ends of the plate F are located guide-studs I 75 I', which are in engagement with the thread B. Between the projections G⁴ and G⁵, I locate within the frame G a series of weights, preferably in the nature of rods or rollers J, which extend transversely of the thread and 80 of the plate F. These rods do not entirely fill the space between the projections G⁴ and G⁵, and are therefore capable of shifting or rolling lengthwise of the plate F. (See Fig. 1.) Preferably the rollers are also capable 85 of an endwise shifting movement transversely of the plate F, as will be understood by reference to Fig. 3.

The thread is inserted into the tension device through the slot G³ and is passed under 90 the rollers J, so as to rest upon the plate F. In order that this may be done, the projections G⁴ and G⁵ do not extend inwardly as far as the edges of the plate F. The rollers J exert a pressure on the thread by their 95 weight, and this pressure may be regulated by employing a greater or smaller number of these rollers. The tension varies but little with the speed given to the thread, and if the thread is started at a high rate of speed 100 there is very little danger of breakage, owing to the fact that the rollers J do not simply

turn upon their axes, but are capable of traveling lengthwise of the plate F until they engage the projections G⁴ or G⁵. Furthermore, in case of a sudden pull one or more of the 5 rollers would mount upon the others, thus avoiding any excessive strain upon the thread. The movement of the rollers transversely of the plate F also contributes to minimize strains.

10 The arrangement of the axes of the spools A and D at an angle to each other, as shown in Fig. 1, enables me to employ a high rate of speed while keeping the spool A stationary. The thread may be straight between 15 the guide C and the spool D, or, if desired, the tension may be increased by causing the thread to form a bend either at the guide-stud I or at the stud I', or both, as indicated by dotted lines in Fig. 2.

20 The improved tension device hereinbefore described is very simple in construction and can be readily taken apart for cleaning and repairs.

25 Various modifications may be made without departing from the nature of my invention.

What I claim as new, and desire to secure by Letters Patent, is—

1. A tension device comprising an approximately horizontal flat supporting element on 30 which the thread is adapted to rest, and loose weights adapted to bear upon the thread from above and to travel lengthwise of the thread.

2. A tension device comprising a frame having a lateral slot or opening so that the thread 35 may be introduced sidewise, a supporting-plate adjacent to said slot, and loose weights arranged to travel lengthwise of the thread and to press it against said supporting-plate.

40 3. A tension device comprising a supporting element on which the thread is adapted to rest, loose weights bearing on said thread and extending transversely thereof, said

weights being adapted to travel lengthwise of the thread, and stops or projections for limiting the movement of the said weights lengthwise of the thread. 45

4. A tension device comprising a supporting element for the thread, loose rollers arranged to travel lengthwise of the thread and 50 adapted to press the same against said supporting element, and a frame having projections or stops against which said rollers are adapted to abut.

5. A tension device comprising a supporting member for the thread, loose weights for pressing the thread against said supporting member, and guides arranged to engage the side of the thread adjacent to the ends of the portion which is engaged by the said weights. 60

6. A tension device comprising a supporting member for the thread, a plurality of sets of rollers for pressing the thread against said supporting member, and a frame having projections or stops for limiting the movement of 65 said rollers and for separating one set of rollers from the other, said frame being also provided with apertures allowing access to the rollers.

7. A tension device comprising a base provided with a supporting element for the thread, a frame detachably secured to the base, and spaced therefrom at one end to form a slot for the sidewise insertion of the thread, and loose rollers extending transversely of 75 the thread and adapted to press the same against the supporting element, the movement of the said rollers being limited by the said frame.

In testimony whereof I have hereunto set 80 my hand in the presence of two subscribing witnesses.

WILLIAM S. WELLS.
